(57) **CLAIM**

The ornamental design for a flat iron, as shown and described.

DESCRIPTION

FIG. 1 is a perspective view of a flat iron showing our new design, shown in a closed position;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a top, front perspective view thereof, shown in an open position; and,

FIG. 9 is a bottom, rear perspective view thereof, shown in an open position.

The broken lines in the drawings depict portions of the flat iron that form no part of the claimed design.
